GASEOUS ELECTRIC DISCHARGE DEVICE

Kurt Wiegand, Berlin-Tempelhof, Germany, assignor to General Electric Company, a corporation of New York

Application July 16, 1935, Serial No. 31,711
In Germany July 31, 1934

1 Claim. (Cl. 176—122)

The present invention relates to gaseous electric discharge devices generally and more particularly the invention relates to such devices the gaseous atmosphere of which consists of or comprises a metal vapor and the container of which is at an elevated temperature during the operation of the device.

It is advantageous to provide a source of heat for the container of such devices and a ballast resistance connected in series with said lamp and mounted on the external surface of said container is useful for this purpose. The object of the present invention is to provide a gaseous electric discharge device having a resistance mounted on the container thereof which device is of simple, compact structure and is inexpensive to manufacture. Another object of the invention is to provide a gaseous electric discharge device of the above type which is safely handled particularly in mounting the lamp. Still further objects and advantages attaching to the device and to its use and operation will be apparent to those skilled in the art from the following particular description.

In accordance with these objects the invention comprises an elongated, tubular container having a longitudinal passage in and extending along the wall thereof and divided from the passage in said lamp in which the gaseous electric discharge takes place. A resistance, such as a helically coiled filament, is mounted in said passage and is connected in series with the discharge in the device. The resistance heats the wall of the container to improve the efficiency of the device.

In the drawing accompanying and forming part of this specification an embodiment of the invention is shown, in which

Fig. 1 is a front elevational view of a gaseous electric discharge lamp device embodying the invention.

Fig. 2 is a sectional view along the line 2—2 of Fig. 1.

Fig. 3 is a similar view with various parts of the lamp removed, and

Fig. 4 is an end sectional view of another form of container useful in the device illustrated in Fig. 1.

Like numbers denote like parts in all the figures.

Referring to Figs. 1, 2, and 3 of the drawing the gaseous electric discharge device comprises an elongated tubular container 1 having a gaseous filling therein, such as argon, neon or krypton, or a mixture thereof, and a quantity 2 of vaporizable material, such as mercury, sodium, cadmium, magnesium, or zinc, the vapor of which

is light emitting during the operation of the device. Stems 3 and 4 are fused into the ends of said container 1 and have supports 5 and 5' and 6 and 6' sealed into the pinch parts 3' and 4' thereof respectively. Tubular sheet metal electrodes 7 and 8 are attached to said wires 5 and 5', 6 and 6' respectively. Said wires 5 and 6 are current leads for said electrodes 7 and 8 respectively. Said container 1 has bases or caps 16 and 19 of insulating material, such as porcelain fastened to the ends thereof. A tube 9 of appreciably smaller diameter than that of said container 1 is fused to said container 1 and extends along the length thereof. When desired, said container 1 and said tube 9 are formed in one operation. Two helically coiled resistance wires 10 and 11 are mounted in the passage in said tube 9. One end of said resistance 10 is connected to current lead 5 of said electrode 7 and the other end thereof is brought out of the tube 9 through the holes 12 (Figs. 2 and 3) adjacent the center of said tube 9 and is fastened to the metal cap 14 cemented on the container 1. Similarly one end of the resistance 11 is connected to the lead 6 of the electrode 8 and the other end thereof is fastened to the cap 15 likewise fastened to the container 1. Current supply leads for the lamp are clamped to the caps 14 and 15 by the nuts 16 and 17 when mounting the lamp and the bases 16 and 19 are inserted in sockets in the fixture in which the lamp is mounted.

The container 1 illustrated in Fig. 4 of the drawing has a hollow, cylindrical, gutter-like depression 20 extending along the length thereof which opens outwardly. Resistances 10 and 11 are mounted in the depression 20 and the slit in said depression is closed by a body of heat resisting, electrically insulating material, such as asbestos cement to prevent any accidental contact with the resistances 10 and 11. The other details of the lamp having this form of container are the same as those of the lamp shown in Fig. 1.

The resistances 10 and 11 serve as ballast for the gaseous electric discharge between said electrodes 7 and 8 and during the operation of the lamp the heat emitted by said resistances 10 and 11 is utilized to heat the walls of container 1 to a higher temperature than would be the case if said resistances were mounted remote from said container 1. The vapor pressure in the lamp and the efficiency thereof are thus higher and the lamp can be successfully started and operated in lower ambient temperatures.

What I claim as new and desire to secure by Letters Patent of the United States, is:—

A gaseous electric discharge device comprising an elongated tubular container, electrodes sealed therein a gaseous atmosphere therein, the wall of said container having a passage therein closed off from the discharge chamber and extending

along the length thereof and a ballast resistance mounted in said passage, one end of said resistance being connected to one of said electrodes and the other end thereof being connected to a contact fastened adjacent the mid-part of said container.

KURT WIEGAND.
